ATTORNEY.

UNITED STATES PATENT OFFICE.

HENRY W. MOULTON, OF JACKSON, MICHIGAN.

CORSET-CLASP.

SPECIFICATION forming part of Letters Patent No. 257,969, dated May 16, 1882.

Application filed January 11, 1882. (Model.)

To all whom it may concern:

Be it known that I, HENRY W. MOULTON, of Jackson, in the county of Jackson and State of Michigan, have invented new and useful Improvements in Corset-Clasps; and I do hereby declare that the following is a full, clear, and exact description thereof, reference being had to the accompanying drawings, which form a part of this specification.

10 The nature of this invention relates to new and useful improvements in corset-clasps; and the invention consists in the peculiar construction and combination of parts, as more fully hereinafter set forth.

15 Figure 1 is a perspective view of my improved shield ready for attachment to a corset. Fig. 2 is a front view of a section of a corset provided with my shield; and Fig. 3 is a cross-section on the line $x x$ in Fig. 2, showing the 20 manner of securing the shield.

In the accompanying drawings, which form a part of this specification, A represents one of the busks in the front of a corset, inclosed in a pocket, as usual, with the loop a riveted 25 to such busk, with the loop portion projecting beyond the edge through the fabric of the pocket.

B represents the fellow busk in a pocket upon the other adjoining portion of the front of 30 the corset, and this busk is provided with a stud, b , which in operation engages with the loop upon the opposite busk, the stud projecting through the front of the pocket, the parts

described being of the usual construction. As thus constructed, the friction caused by 35 locking the parts together upon the exposed part of the pocket which covers the busk B soon wears out the fabric. To obviate this I employ a shield, C, stamped or cut out of thin sheet metal and provided with fastening-lips, 40 which is clasped around the front and rear edge of the pocket and inclosed busk, and with a hole which allows such shield to pass over the stud, thus interposing at very slight cost such metal plate for the purpose of preventing wear of the fabric. 45

What I claim as my invention is—

1. As an improved article of manufacture, the metal shield C, provided with fastening-lips, and having an aperture larger than the 50 head of the fastening-stud of a corset-busk, adapted to be applied to a corset over the fabric after the fastening-stud attached to the busk has been secured in place, substantially as and for the purpose specified. 55

2. The combination, with the busk B and the stud b thereof, of the shield C, made entirely separate from the busk and stud, and secured to the corset over the fabric and stud after the busk and stud have first been secured within 60 said corset fabric, substantially as and for the purpose specified.

HENRY W. MOULTON.
